HOSPITAL BED

William A. Hillenbrand, Franklin County, Ind.,
assignor to Hill-Rom Company, Inc., Batesville,
Ind., a corporation of Indiana

Application April 3, 1943, Serial No. 481,717

4 Claims. (Cl. 5—69)

This invention relates to bed springs and is particularly concerned with a sectional spring of the hospital type in which means are provided for raising the head and foot sections of the spring to add to the comfort of the patient and to facilitate reading, eating and the like. The invention is primarily concerned with improved means for manipulating the sections of the spring for these purposes.

For many years hospital bed springs have been almost completely standardized in construction. The conventional type of spring, which is known in the trade as a "Gatch" spring, taking its name from the inventor of the structure, is operated by a screw and nut arrangement in which the entire weight of the portion of the spring being elevated and the patient resting on that portion of the spring is carried by the screw and nut. In this type of structure, in order to provide even a reasonable degree of ease of operation it is necessary to have a large screw, a large nut and a very large crank to transmit the power necessary to provide the elevation. This is particularly true in the case of the head section of the bed. This section is conventionally longer than any of the other sections and bears a disproportionate amount of the patient's weight. For this reason the elevation of this section utilizing a screw and nut arrangement requires heavy, large and serviceable parts as well as a very decided amount of manual effort, particularly at the beginning of the elevating operation.

The use of these large and heavy parts is objectionable for reasons of economy of manufacture, and also for the reason that the large cranks which are required necessarily extend a considerable distance beyond the foot of the bed and constitute an obstacle which frequently is bumped by nurses and other attendants, and visitors. Also these large cranks are unsightly. In order to overcome the objections to the use of large cranks, it has been proposed to provide a crank which telescopes or folds. While this is a theoretical solution, in practice the nurse and attendant seldom go to the trouble of telescoping or folding the cranks and usually allow them to protrude from the end of the bed in cranking position.

In springs of the standard type the manipulation of even a large crank requires a very appreciable amount of physical effort, particularly in the case of a heavy patient or when the mechanism has become slightly worn or rusted. Since the cranking is usually done by nurses of comparatively slight physical strength and they

are frequently called on to manipulate scores of cranks in the course of a day, a considerable physical strain is imposed on the nurses engaged in these duties.

5 Another objection to the conventional type of spring is that the section next to the head section which will hereinafter be called the head middle section remains stationary and horizontal to the ground at all times. As a result, when 10 the head section is elevated the patient tends to slide toward the foot of the bed. In order to counteract this tendency and keep the patient comfortable it is usually necessary to raise the foot section every time the head section is raised.

15 The spring of the present invention overcomes each of these various objections. Utilizing a novel leverage arrangement, it is proposed to utilize the weight of the patient as a primary source of power in elevating the head portion of

20 the spring. Although the construction of the invention utilizes a screw and crank mechanism as in the prior art, the weight of the patient rather than the screw is the primary lifting means and the screw mechanism performs only 25 a secondary function in the operation. For this reason it is possible to provide much smaller and less obtrusive mechanical parts while the manual effort necessary to manipulate them is very 30 much less than in the case of the present standard construction.

Another advantage of the present invention is that it provides for the tilting of one or more 35 of the middle sections of the spring toward the head of the bed. This gives the patient a chair-seat position which is infinitely more comfortable than the rigid inclined position provided in structures in which the middle portions of the spring remain horizontal to the ground. The 40 tilting and lowering of these middle sections also tends to overcome the tendency of the patient to slide toward the foot of the bed, and, accordingly, it is unnecessary to raise the foot section simply to overcome this tendency. As a practical 45 matter, in springs of the type of the invention the raising of the foot section is comparatively a secondary function of the spring, whereas in the springs of the prior art the foot section is raised almost as much as the head section.

50 Having in mind the accomplishment of the purposes described, the particular objects of the invention may be enumerated as follows:

One of the objects has been to provide a hospital bed spring which is so constructed that the weight of the patient is utilized as a factor

in the provision of the power means for elevating and depressing portions of the spring.

Another object has been to provide a spring in which the middle sections of the spring may be lowered and inclined toward the head of the bed thereby giving the patient a more comfortable position.

Another object has been to overcome the tendency of the patient to slip toward the foot of the bed upon the elevation of the head section without utilizing the foot elevating means for this purpose.

Another object has been to provide a spring in which the mechanical parts are substantially smaller than has been possible heretofore and one in which the physical effort necessary to manipulate the parts may be substantially less.

Another object has been the provision of a spring in which the operating parts such as the crank handle may be smaller, less obtrusive, and less unsightly, and in which a material saving in manufacturing cost is obtained due to the reduction in size of these elements and other factors.

Other and further objects and advantages will be apparent from the further and more detailed description of the invention when considered in conjunction with the drawings in which:

Figure 1 is a top plan view of a spring illustrating a preferred embodiment of the invention.

Figure 2 is a sectional view along the line 2—2, Figure 1.

Figure 3 is a sectional view along the line 3—3, Figure 1, showing the foot sections of the spring in elevated position.

Figure 4 is a sectional view similar to Figure 2 showing the head section of the spring in elevated position and the middle sections in inclined position.

Figure 5 is a sectional view similar to Figure 2 illustrating a modified form of the construction of the invention.

Figure 6 is a sectional view similar to Figure 4 illustrating the same modification with the head section of the spring elevated and the middle sections inclined.

Figure 7 is an enlarged sectional view showing the details of construction of the crank, screw, and nut mechanism shown in Figures 2, 4, 5 and 6.

Describing the invention in detail, a lower spring frame is indicated generally at 10. This frame is conventional in construction and comprises side rails 11 and end rails 12. A spring web 13 of conventional construction is affixed to the side and end rails of each of the various upper sections which comprise the spring of the invention. A number of lateral braces 14 are extended across the sections and secured to the side rails. These braces may have flattened ends as shown and are bowed downwardly so as not to interfere with the flexing of the spring web 3.

The sections of the upper spring assembly which embrace the invention rest generally on the frame and may be four in number. From the foot to the head of the bed these sections have been designated as the foot section 15, the foot middle section 16, the head middle section 17 and the head section 18. In the preferred embodiment, these sections are joined together, and supporting the spring web 13, comprise the structure on which the patient rests.

The foot section 15 comprises side rails 19 and an end rail 21. Extending beneath the side and end rails of the foot section is a U-shaped rail

member 20. This rail member has racks 22 formed along each of its sides. Legs 23 are secured to the sides of the U-shaped member by the bolts 24. At the lower end of these legs are rollers 25 journaled on the pins 26. The rollers rest on the top of the side rails 11 of the lower frame. The entire foot section is pivoted on the pins 27, and, if desired, it may be inclined upwardly as shown in dot-dash lines, Figure 2, and supported in elevated position by the prop 28 which may be engaged selectively with the various notches in the rack. This positioning of the foot section is accomplished manually and is intended for use only when for some reason it is desirable to elevate the feet of the patient.

The pin 27 also serves to join the foot section to the foot middle section 16 of the spring. In this latter section the side rails are designated as 29. These side rail sections 29 are pivotally connected to side rail sections 30 of the head middle section 17 by means of pins 31 which pass through the rail sections 29 and the upper ends of angle brackets 32 which in turn are securely fixed to rail sections 30. The rail sections 29 are thus free to pivot upwardly as shown in Figure 3.

Rail members 33 intermediate the plane of the bottom side rails 11 and the plane of the upper rail sections 29 and 30 are securely fixed to the bottom portion of angle brackets 32 and similar angle brackets 34 by means of rivets or like fastening means 35. The brackets 34 are fixed to the forward ends of the rail sections 30 as at 36. As shown in Figure 1, angle brackets 32 and 34 extend inwardly from the side rails to eliminate any interference between rail members 33 and the lower side rails 11.

Arm sections 37 are rigidly secured to the foot end of the rail members 33 by means of rivets or the like 38. These arm sections 37 are loosely journaled on a shaft 39 which extends laterally across the bed and has rollers 40 on each end thereof engaged in channel sections 41 fixed to 42 and supported by feet 42 which are fixed to the lower side rails 11. At the forward or head end of the rail member 33 a vertical arm 43 fixed thereto is pivotally connected to one end of an arm 44 by means of pin 45. The arm 44 is fixed at its other end to rock shaft 46 supported by trunnions 47 fixed to the lower side rails 11. Also rigidly secured to the rock shaft 46 as by welding are the head elevating arms 48 to which rollers 49 are pinned as at 50. The rollers 49 are adapted to engage the lower surface of the side rails 51 of the head section 18. The side rails 51 of this section are pivotally connected to the side rails 30 of the head middle section 17 by means of pins 52. Vertical supports 53 are secured to the under surface of the side rails 51 near their front ends and the lower ends of these supports rest on the upper surfaces of the side rails 11 when the head section is in the position shown in Figure 2.

From this description, it will be noted that a weight or pressure applied to the head middle section 17 of the spring as indicated by the arrow in Figure 2 will elevate the head section and drop the two middle sections as shown in Figure 4. The weight pressure is transmitted to the arms 44 from the head middle section 17 by means of the angle brackets 32 and 34, rail members 33 and the vertical arms 43. The ends of the arms 44 being pivotally connected to vertical arms 43 are thus moved downwardly, rocking the shaft

46 which in turn swings the head elevating arms 48 upwardly to raise the head section 18.

When a patient is placed on the bed the seat and thigh sections, which comprise a very substantial proportion of the patient's weight, are positioned on the two middle sections 16 and 17, and through the leverage arrangement just described counterbalance the head section 18 and the weight disposed thereon. However, a very slight shifting of weight by the patient will tend to raise the head section and drop the middle section without aid of an attendant, or with very little effort an attendant can raise the head section manually. As the head section is being raised the patient's weight is increasingly concentrated on the middle sections. When in a sitting position the weight is almost entirely concentrated on the middle sections and the head section will remain in elevated position without additional support.

However, it would be impractical to have the head section free to be elevated by a mere shifting of weight by the patient as this could occur accidentally while the patient is sleeping or while changing his position in bed. The elevation of the head section is therefore controlled through the tubular link 54 which is pivotally attached to an arm 55 by means of a pin 56. The arm 55 is securely attached, as by welding, to the rock shaft 46. A rod 57 passes through an opening 58 in the lower foot end rail 12 and has a screw threaded section 59 which engages a nut 60 fixed in the end of the tubular link 54 (Figure 7). The rod 57 is supported in position by collars 61 pinned to the rod on each end of a journal block 62 which in turn is supported by brackets 63 fixed to the underside of the lower end rail 12. Pins 64 extending outwardly from each side of the block 62 are rotatably journaled in apertures in the brackets 63. The rod 57 is actuated by the crank handle 65 at the rear end thereof.

In elevating the head portion of the spring the crank handle is turned and the tubular link 54 is moved forwardly by the engagement between the screw threaded portion 59 of the rod and the nut 60. This forward movement of the link rocks the shaft 46 which in turn raises the elevating arms 48 thereby forcing the entire head section upwardly in the manner illustrated in Figure 4. As the head section moves upwardly the rail section 33 is pivoted downwardly on the shaft 39, by the arms 43 and 44. Thus the same action occurs as when the operation is performed solely by the shifting of weight by the patient or the manual raising of the head section by an attendant. However, the screw, crank, nut and tubular link mechanism just described holds the head section 18 rigidly in any desired position, and the operation of this mechanism requires very little physical effort on the part of an attendant as the patient's weight through the leverage arrangement counterbalances the power required to lift the head section. Even in the most extreme case of a very heavy patient and a nurse of very slight physical strength the head raising operation is very easily accomplished as the excessive weight serves to aid in the raising operation.

In the form of the invention shown in Figures 1, 2 and 4 the joint between the rail sections 51 and 30 may eventually contact the top surface of the lower side rails 11 as at 66 to act as a stop on the upward movement of the head section. However, various other forms of stop means may be provided. The degree of angulation formed by the head section 18 and head middle section 17 at the conclusion of the head raising operation

may be adjusted in a number of ways. By varying the length or position of rail members 33, arms 43 and 44, rock shaft 46 or by various other means this adjustment can be accomplished. The arm 43 may be omitted entirely and the arm 44 fixed to the rock shaft 46 may be pivotally connected directly to the rail element 33. This form of construction is illustrated in Figures 5 and 6.

In the form illustrated in Figures 1, 2 and 4, as the rail elements 33 and the arms 44 are swung downwardly the four top sections 15, 16, 17 and 18 first creep toward the foot of the bed and then toward the head. As the arms 44 approach a position parallel to the bottom rails 11 the top sections creep toward the foot, but as these arms continue swinging downwardly and pass a position parallel to the rails 11, the top spring sections creep toward the head. This is due to the fact that the distance between the rock shaft 46 and shaft 39 is first increased until as the arms 44 pass a position parallel to the rails 11 the distance between these shafts is decreased, the shaft 39 being drawn toward the rock shaft 46. This creeping movement is transmitted to the top spring sections by the rail elements 33 and the angle brackets 32 and 34 joining the rail elements 33 and the top spring sections. When the arm 43 is omitted as in Figures 5 and 6 and the arms 44 are parallel to the rails 11 at the start of the head raising operation, the top sections creep only in one direction, toward the head of the bed.

To accommodate this creeping action the foot elevating shaft 39 carries rollers 40 on the ends thereof which rotatably engage in channel sections 41 fixed to the side rails 11 by means of feet 42. Accordingly, the shaft 39 travels in a plane which always is parallel to the plane of the lower side rails 11 as the top sections creep either backward or forward.

40 The arms 67 having their upper ends loosely engaged about the shaft 39 have their lower ends fixed to a cross support rail member 68 by means of angle brackets 69 fixed to the rail member 68 as at 70. These angle brackets 69, the arms 67 and support brackets 71 may be bolted together as shown at 72. Support brackets 71 extend outwardly from the arms 67 and are slidably engaged over the top surface of the lower side rails 11. The sections of these brackets overlying the side rails 11 are shown at 74 in Figure 1. This construction further facilitates the creeping of the spring sections.

55 The elevation of the foot and foot middle sections of the spring is best illustrated in Figure 3. As shown, a rod 75 is inserted through a tube 76. This rod is actuated by the crank handle 77 and is supported under the lower end rail 12 of the foot section of the spring by collars 78 in exactly the same manner as is the rod 57 of the head elevating mechanism. At its forward end, the tube 76 is connected to a rod 79 by a universal joint 80. The rod 79 is supported by a journal block 81 and is held in place by collars 82 pinned to the rod on each end of the block. 60 The block 81 is rotatably journaled between brackets 83 fixed to the cross support rail member 68. Pins 84 extend outwardly from each side of the block to engage apertures in the brackets. The forward end of the rod 79 is screw threaded and engaged by a nut 85 rotatably fixed between arms 86. The arms 86 are rigidly fixed as by welding to the shaft 39. The foot elevating arms 87 may be similarly fixed to the shaft 39 toward the ends thereof and carry rollers at their upper ends engaging the lower surfaces of the rail sec-

tions 29 of the foot middle section adjacent the joint between the foot section 15 and the foot middle section 16.

The end of the tube 76 adjacent the handle 77 is slotted as at 88. A pin or screw 89 is inserted through the slot 88 and fixed in the rod 75. As the crank handle 77 is actuated the pin or screw 89 engages the walls of the slot and transmits the motion to the tube 76. The screw threaded rod 79 is actuated from the tube 76 through the universal joint drawing the nut 85 and arms 86 toward the foot end of the bed thereby rocking the shaft 39 and swinging the foot elevating arms 87 upwardly toward the head section and raising the foot middle section 16 and the foot section 15 to the position shown in Figure 3. A collar stop 95 is pinned to the forward end of the screw threaded rod 79.

Since the top sections of the spring creep backward and forward as the head section is being elevated, the foot elevating mechanism must move or creep with it to keep the parts in proper operative alignment with the foot and foot middle sections 15 and 16. As described previously the shaft 39 moves in a plane parallel to the plane of the bottom side rails 11 when the head is elevated. Since the foot elevating arms 87 are rigidly fixed to this shaft and arms 67 carrying the foot elevating mechanism are loosely engaged about the shaft 39, the arms 87 and the foot elevating mechanism move or creep along with the top sections. As this mechanism creeps, the tube 76 slidably engaged about the shaft 75 is free to move or slide in both directions while still maintaining an operative connection with the crank carrying shaft 75 through engagement of the pin or screw 89 with the walls of the slot 88.

In the modified form of the invention shown in Figures 5 and 6, creeping of the head and middle sections of the spring is entirely eliminated. The rail members 33 are slotted as at 90. The pins 91 carried by the arms 44 are loosely engaged in these slots and as the arms 44 swing downwardly the pins ride in the slot and the movement terminates when the pins reach the ends of the slots.

In this modified form the foot elevating shaft 39 is supported by trunnions 92 fixed to the lower side rails 11. As shown in dot-dash lines, the foot elevating mechanism may be identical with the head elevating mechanism. A tubular link 93 is pivotally pinned to an arm 94 which is fixed rigidly to the shaft 39. As the shaft is rocked and the elevating arm 87 moves forward the tilting of the foot middle section elevates the foot section, and pulls it toward the head of the bed on the rollers 25. However, the middle sections do not creep during either of the elevating operations, and, accordingly, the construction of the modification may be substantially simplified over that shown in Figures 1-4, inclusive.

Having described my invention, I claim:

1. In a hospital bed spring, a plurality of connected frame sections pivotally interconnected in end to end relationship, means for tilting the

sections in opposite directions to form a trough therefrom, comprising a rock shaft disposed beneath one section adjacent its inner end, arms secured to said shaft and arranged in V configuration, one of said arms engaging the outer end of an end section of the spring and the other of said arms being connected to a section contiguous to the end section, whereby upon rocking of the shaft the outer end of the end section is elevated and the inner end of the end section and the adjoining end of the contiguous section are depressed and means for rocking said shaft.

2. In a hospital bed spring, a plurality of frame sections pivotally interconnected in end to end relationship for hinging movements with respect to one another, a rock shaft disposed beneath one of the sections and extending laterally of the frame, arms extending from said rock shaft in V relationship to one another, one of said arms engaging the outer end of an end frame section and the other being pivotally connected with a section contiguous to said end section whereby rocking movement of the shaft effects elevation of the outer end of said end section and depression of the contiguous section and the adjoining end of the end section, and screw means for rocking said rock shaft.

3. In a hospital bed spring a plurality of frame sections arranged longitudinally, said sections including a head section and a middle section pivotally connected thereto, a rock shaft disposed beneath the head section and extending laterally of the frame, arms pinned to the rock shaft and arranged in Y configuration, one of said arms engaging the outer end of the head section, one engaging the middle section and one extending downwardly, a tubular link extending longitudinally of the frame and secured to said downwardly extending arm and means for moving said link longitudinally for rocking the shaft and tilting the head section of the frame.

4. In a hospital bed, a frame, a plurality of panel sections arranged in end to end relationship above said frame, including a head panel section and a middle panel section pivotally connected thereto, a rock shaft supported by said frame beneath said head panel section, pairs of arms arranged in V configuration extending from said rock shaft at opposite sides of said frame, one of the arms of each pair engaging the outer end of the head panel and the other of the arms of each pair engaging the middle panel at points adjacent the head panel whereby the outer end of said head panel is elevated and the end of the middle panel adjacent the head panel is depressed and moved toward the head panel upon rotation of the rock shaft, and means for rotating said rock shaft, comprising another arm extending downwardly therefrom, a tubular ring supported from said frame and secured to said downwardly extending arm, and screw means for moving said ring longitudinally of said frame.

WILLIAM A. HILLENBRAND.
